UNITED STATES PATENT OFFICE.

JULIUS LEISEL, OF CHARLOTTE, NORTH CAROLINA.

DYEING-MACHINE.

1,010,274.

Specification of Letters Patent. Patented Nov. 28, 1911.

Application filed July 21, 1909. Serial No. 508,704.

To all whom it may concern:

Be it known that I, JULIUS LEISEL, a citizen of the United States, and a resident of Charlotte, in the county of Mecklenburg and State of North Carolina, have invented a new and Improved Dyeing-Machine, of which the following is a full, clear, and exact description.

The invention relates to machines for dyeing cotton and wool in the raw or in the manufactured state, and such, for instance, as shown and described in the Letters Patent of the United States, No. 782,147, granted to me on February 7, 1905.

15 The object of the present invention is to provide a new and improved dyeing machine, arranged for dyeing either loose material, or yarns wound on a beam, and provided with a circulating system for circulating dye liquor or clear water through the vat and the material contained therein, and provision is made by an overhead mechanism for manipulating the perforated vat cover and the false bottom, between which 20 the material is laid, the said circulating system having a pump adapted to be driven by a reversible motor, which is also used for actuating the said overhead mechanism in either direction.

30 A practical embodiment of the invention is represented in the accompanying drawings forming a part of this specification, in which similar characters of reference indicate corresponding parts in all the views.

35 Figure 1 is a side elevation of the dyeing machine, part of the foundation being shown in section; Fig. 2 is an elevation of the right-hand end of the machine, the motor and driving gear for the overhead mechanism being omitted; Fig. 3 is a sectional side elevation of the machine, arranged for dyeing loose material; Fig. 4 is a like view of the same and showing the perforate cover and perforate false bottom in raised 40 positions; Fig. 5 is a sectional plan view of the same, on the line 5—5 of Fig. 1; Fig. 6 is a sectional side elevation of the double valve and by-pass for connecting the outflow pipe of the circulating pump with the storage tank pipe; Fig. 7 is a cross section of the same on the line 7—7 of Fig. 6; Fig. 8 is a sectional side elevation of the double valve for connecting the well pipe with the return pipe of the circulating pump; Fig. 45 50 55

9 is a sectional side elevation of the latch for locking the perforate cover in raised po-

sition; and Fig. 10 is a sectional side elevation of the dyeing machine, arranged for dyeing yarns wound on a slasher beam.

A vat A, of rectangular or other suitable shape, supports at its bottom A' a false perforated bottom B, having lugs B' adapted to rest on the vat bottom A', to support the false perforated bottom B a distance above the vat bottom A', with a view to form a 60 circulating space or a chamber A² for the water, dye liquor or other liquid, as herein-after more fully described. When dyeing loose material, it rests on the false bottom B, and is engaged on top by a perforate 65 cover C, to confine the loose material between the false bottom B and the said cover C a distance below the level of the liquor in the vat. The cover C is provided at its ends and sides with an upwardly extending annular flange C', and on the bottom of the cover along its margin is arranged a tongue C² adapted to engage a corresponding groove A³, formed in an outwardly-extending annular offset A⁴ on the upper portion 70 of the vat A, as plainly indicated in Figs. 3 and 4. A packing C³ of suitable material is interposed between the flange C' and the offset A⁴, to provide a tight joint between the flange C' and the offset A⁴, so that the 75 circulating liquid is not liable to leak past the joint, and consequently passes through the perforations in the cover C.

In the circulating space A² extend a series of nozzles D, passing through the bottom A' and connecting with an outflow pipe D', leading from a circulating pump E of any approved construction. The return pipe D² for the circulating pump E connects with an overflow chamber F arranged on 90 the right-hand end of the vat A, and having its upper or inlet end opening into the vat at a distance above the offset A⁴ and the cover C, when the latter is in position in the vat, as indicated in Fig. 3. The entrance end of the overflow chamber F is covered by a grated or slatted cover F', preferably inclined, so as to insure a ready 95 flow of the dye liquor or other liquid from the upper end of the vat A into the overflow 100 chamber F. Now when the loose material to be dyed is in position in the vat between the bottom B and the cover C, and the vat is filled with dye liquor and the pump E is started, then the dye liquor is forced 105 through the pipe D' and the nozzles D into the circulating space A², from which the 110

liquor rises through the perforated false bottom B and through the material, to finally pass through the openings in the cover C and through the slots in the cover F' into the overflow chamber F and by way of the pipe D² back to the circulating pump E. By making the cover F' in the form of spaced slats, any loose matter or material carried along with the dye liquor and striking the inclined slats, is pushed up the same and out of the direct flow of the dye liquor. The operator with a rake can readily remove the gathered extraneous matter.

The nozzles D are preferably four in. number and are grouped around a well G, the same as described in the Letters Patent of the United States above referred to, so that further description of the same is not deemed necessary, it being understood that the liquid in the circulating space A² is caused to travel in a circular path around the well G, for the foreign insoluble or other extraneous matter in the liquid to gravitate toward the well G, to finally drop into the same. The lower portion of the well G leads to a pipe G², connected by a double valve H with the return pipe D², and which double valve H serves to close the pipe G² or to connect the same with the pipe D², at the time the double valve closes the return pipe D² to the overflow chamber F, and connects the pipe G² with the pipe D² and the circulating pump E. When this connection is made, the outflow pipe D' is closed to the nozzles D and the circulating space A² by a double valve I, which serves to connect the circulating pump E with a pipe I' leading to a storage tank.

The return pipe D² is connected by a pipe J, having a valve J', with a water supply, and a valve D³ is arranged in the return pipe D², between the valve H and the pipe J, to close the pipe D² by the valve D³ to the valve H. Now when the valve J' is opened and the valve I connects the pump E with the pipe D', and the pump is started, then water is pumped by way of the pipe J, pump E, pipe D' and nozzles D into the circulating space A², to pass through the perforated false bottom B, the material, and the covers C and F' into the overflow chamber F, from which leads the pipe D² now closed to the valve D³. From the overflow chamber F leads a drain pipe K, having a valve K' which is now opened, so that the wash water circulating through the material and passing into the overflow chamber F can flow by way of the pipe K to a suitable place of discharge.

By the arrangement described, the dye liquor can be readily circulated through the vat and the material contained therein for any desired length of time, to insure a through dyeing of the material, and when the dyeing is completed, the attendant in

charge changes the positions of the valves to allow the pump to pump the liquor by way of the pipe I' to a storage tank, for further use. If the liquor is, however, spent and of little or no value, it can be run to waste. After the liquor is removed, the attendant again changes the valves, to connect the water supply pipe J with the circulating pump E, for the latter to force clear water through the vat and the material contained therein, the water after passing through the material and into the overflow chamber F being allowed to drain off by way of the now open drain pipe K.

In order to heat the dye liquor, use is preferably made of a steam heating pipe L, arranged in the overflow chamber F and connected with a suitable steam supply. By this arrangement undue pressure from expansion of the heated liquor or the formation of gases is prevented, as the overflow chamber F is open at the top to the atmosphere. In order to avoid undue pressure from gases in the vat A, an escape port a is formed in the partition F² separating the vat from the overflow chamber F, the port connecting the vat with the overflow chamber immediately below the offset chamber A⁴ (see Fig. 3).

When dyeing yarns wound on a slasher beam M, the latter rests on the false bottom B, and use is made of a non-perforate cover C⁴, adapted to be seated on the offset A⁴, the same as the cover C (see Fig. 10), as previously explained. The beam M is provided with a hollow perforated hub M', end flanges M² and a shaft M³ extending centrally in the hub M', the left end of which is closed and the right open end is seated against a packing F³ in a seat F⁴, formed in the partition F² and opening into the overflow chamber F. The hub M' is drawn into firm contact with the packing F³ by a wedge M⁴ abutting against the seat F⁴. Now when the pump E is running, the dye liquor is forced into the vat, through the yarn, and by way of the perforated hub M' of the beam M is passed into the overflow chamber F, from which the dye liquor returns to the pump E, to be again sent through the vat and the yarn until the latter is thoroughly dyed. The solid cover C⁴ is secured to the perforate cover C by screws C⁵ or other fastening means, and the cover C is held locked in place, raised or lowered, either when used in dyeing loose material or when carrying the solid cover C⁴ by means hereinafter described in detail.

When dyeing loose material the solid cover C⁴ is dispensed with and the seat F⁴ is closed by a plug M⁵ drawn against the packing F³ by the wedge M⁴ engaging the stem M⁶ of the plug M⁵, as will be readily understood by reference to Fig. 3. The left-hand end of the shaft M³ terminates at the

closed end of the hub M' and is preferably made hollow for the insertion of a journal when using the beam M in a warping machine or a slasher. It is understood that the 5 journal is removed to provide room in the vat A for the beam when shifting the latter axially, as hereafter explained.

The cover C is hung on links N, pivotally connected with bell crank levers N', fulcrumed on a frame O, mounted to swing at O' on the right-hand end of the vat A. The free end of the frame O is adapted to be locked in place by links O² and removable pins O³, of which the links O² are pivoted 10 on lugs A⁵, cast on the left-hand end of the vat A. The bell crank levers N' above mentioned are pivotally connected with each other by a link N², having an angular arm N³ pivotally connected with a nut N⁴, screwing 15 on a screw rod N⁵, mounted to turn in a bearing N⁶, trunnioned on a bracket N⁷, attached to the frame O. A crank arm N⁸ is secured on the screw rod N⁵ and is under the control of the operator for 20 turning the screw rod N⁵, with a view to move the nut N⁴ lengthwise of the screw rod, to impart a swinging motion to the bell crank levers N' by the link N², the swinging motion of the bell crank levers N' causing 25 30 up or down movement of the links N and a corresponding movement of the cover C, to move the latter to or from its seat on the offset A⁴. By the arrangement described, the cover C can be pressed down with sufficient 35 force to insure a proper seating of the cover on the offset A⁴, and to hold the material in position between the cover and the perforated false bottom B. It is also understood that when the solid cover C⁴ 40 is attached to the perforated cover C and the latter is pressed down, then the solid cover C⁴ is firmly seated on the offset A⁴, the joint being rendered tight by the packing C³.

After the cover C is unseated and it is 45 desired to move the cover C out of the vat A and with it the cover C⁴, in case the latter is used, then the frame O is unlocked by withdrawing the pins O³ and swinging the frame O upward into the position shown in 50 Fig. 4, thus raising the cover C clear of the vat. For the purpose mentioned the swing frame O is connected near its free end with ropes or cables P, winding on drums P' secured on a shaft P², journaled in suitable 55 bearings arranged on an overhead frame-work A⁶, supported from the vat A, as plainly indicated in the drawings. On one end of the shaft P² is secured a worm wheel P³ in mesh with a worm P⁴, mounted to 60 rotate loosely on a shaft Q, extending longitudinally and journaled in suitable bearings on the overhead frame-work A⁶. The worm P⁴ is provided with a clutch member P⁵, adapted to be engaged by a clutch member 65 P⁶, mounted to slide on and to turn with

the shaft Q, and engaged by a shifting lever P⁷, fulcrumed on the overhead frame-work A⁶ and under the control of the attendant of the machine. When the shaft Q is rotated and the shifting lever P⁷ is swung 70 outward from its normal position of rest shown in Fig. 1, in the direction of the arrow a' then the clutch member P⁶ is moved into engagement with the clutch member P⁵, to rotate the worm P⁴ and consequently the 75 worm P³, the shaft P² and the drums P', to wind up or unwind the ropes or cables P according to the direction in which the shaft Q is rotated. Thus when the drums P' are rotated to wind up the ropes or 80 cables P, then frame O and with it the perforate cover C are swung upward into the raised position illustrated in Fig. 4, and when the drums P' are rotated in the reverse direction then the ropes or cables P unwind, 85 to allow the frame O and with it the cover C to swing downward into the position shown in Fig. 3, the cover C being independently moved into final position by the operator turning the screw rod N⁵, as previously 90 explained.

The shaft Q is provided at one end with a sprocket wheel Q', connected by a sprocket chain Q² with a sprocket wheel Q³, mounted to turn loosely on the motor shaft R of a 95 reversible motor R' of any approved construction. The sprocket wheel Q³ is provided with a clutch member Q⁴, adapted to be engaged by the clutch member S of a double clutch, mounted to slide on and to 100 turn with the motor shaft R, and controlled by a shifting lever S' under the control of the attendant. The double clutch referred to is also provided with a clutch S², adapted to engage a clutch member E' secured on 105 the shaft E² of the circulating pump E, so that when the clutch member S² engages the clutch member E', then the circulating pump E is driven, and when the double clutch is shifted to the right and the clutch member S engages the clutch member Q⁴, then the sprocket wheel Q³ is driven, and its 110 rotary motion is transmitted by the chain Q² and the sprocket wheel Q' to the shaft Q. Now as the motor R' is reversible, it 115 is evident that the shaft Q can be driven in either direction for turning the drums P', to wind up or unwind the cables or ropes P.

In order to lock the drums P' in position at the time the ropes or cables P are wound up and the cover C is in the raised position shown in Fig. 4, the following arrangement is made: On the worm P⁴ is secured or formed a brake wheel T engaged by a brake band made in sections T¹ and T², pivotally connected with a lever T³ (see Figs. 1 and 2), connected by an adjustable link T⁴ with a bell crank lever T⁵, fulcrumed on the overhead frame-work A⁶, and pivotally connected by a link T⁶ with the lever P⁷, so 120 125 130

that when the latter is swung to the left in the inverse direction of the arrow a' , then the sectional brake band T' , T^2 is closed around the brake wheel T , to hold the worm P^4 against accidental turning. The lever P^7 is adapted to be locked in place in either its normal or brake applied positions, by engaging a notched bar P^8 , shown in Figs. 1 and 2.

- 10 In order to raise and lower the false perforated bottom B in the vat A , and, when dyeing loose material, to swing the said bottom B into an inclined or a discharging position, as shown in Fig. 4, the following arrangement is made: The bottom B is provided on its upper surface with short chains B^2 , B^3 , adapted to be engaged at their outer links by hooks B^4 , B^5 , held on ropes B^6 , B^7 , extending through the joint 20 between the flange C' and the offset A^4 to the outside of the vat, as indicated in Fig. 3. Now after the cover C has been moved into the raised position shown in Fig. 4, the operator takes hold of the ropes B^6 and B^7 25 and pulls the normally folded chains B^2 , B^3 up outward to the top of the vat, to then disconnect the hooks B^4 , B^5 from the chains B^2 , B^3 , and to engage the latter with the hooks U' and V' on the ends of ropes or 30 cables U and V , extending upwardly and winding and unwinding on drums U^2 and V^2 , secured on transverse shafts U^3 , V^3 , journaled in suitable bearings on the overhead framework A^6 . On the shafts U^3 , and V^3 are 35 secured worm wheels U^4 , V^4 , in mesh with worms U^5 , V^5 , mounted to turn loosely on the driven shaft Q , and provided with clutch members U^6 , V^6 , adapted to be engaged by clutch members W and W' , mounted to slide on and to turn with the driven shaft Q . The clutch members W and W' are engaged by shifting levers W^2 , W^3 , connected by links W^4 , W^5 with levers W^6 , W^7 , fulcrumed on the overhead framework A^6 , and arranged in the front and rear of the lever P^7 , previously described. Now when the machine is running, and the shaft Q is rotated, and the cover C has been 45 swung into a raised position, as before explained, and it is desired to lift the false bottom B with the dyed material thereon cut of the vat, then the ropes U' and V' are connected with the chains B^2 , B^3 , as previously explained, and then both levers W^6 , W^7 are shifted simultaneously in the direction of the arrow a' , to move the clutch members W and W' into engagement with the clutch members U^6 , V^6 , to rotate the worms U^5 and V^5 simultaneously and consequently to rotate the worms U^4 , V^4 , the shafts U^3 , V^3 and the drums U^2 , V^2 in unison, to wind up the ropes or cables U and V . When this takes place the perforated false bottom B with the material 50 thereon is gradually lifted out of the vat

A, and when the perforated bottom B is clear of the top of the vat A , then the operator moves the lever W^7 , to normal vertical position, thereby moving the clutch member W^4 out of engagement with the clutch member V^6 to stop the rotation of the worm V^2 and winding up of the rope or cable V . The other rope or cable U keeps on winding up on the drum U^2 , so that the right-hand end of the perforated bottom B 75 is raised while the left-hand lugs B' of the bottom B rest against the left-hand end of the vat A , to serve as a fulcrum for the perforated bottom B , to swing into the inclined discharging position shown in Fig. 4. 80 When this position is reached the operator returns the lever W^6 to the normal vertical position, so that the clutch member W moves out of engagement with the clutch member U^6 , to stop the rotation of the worm U^5 for the time being. Retaining chains B^8 are attached to the under side of the false perforate bottom B at the right-hand side thereof, and the said chains are attached to the bottom A' of the vat at the left-hand side thereof, the chains lying normally slack in the circulating space A^2 . When the false bottom B is raised into discharging position, as above described and shown in Fig. 4, then the chains B^8 are drawn taut and 95 hold the perforate bottom against moving to the right during the time the dyed material slides off the perforate false bottom B . After the material is discharged from the perforated false bottom B , the latter may 100 be returned to the vat, and for this purpose the attendant reverses the motor R' , so as to rotate the shaft Q in the opposite direction. The operator next swings the lever W^6 to the left, to again drive the drum U^2 105 but in a reverse direction, so that the rope or cable U unwinds to allow the perforated bottom B to swing downward into a horizontal position, and when this is reached the operator swings the lever W^7 to the left, 110 to engage the clutch member W' with the clutch member W^6 , to rotate the drum V^2 in a reverse direction, that is, in the same direction in which the drum U^2 is running, so that both ropes or cables U and V unwind together and thereby lower the perforated bottom B in the vat A until the lugs B' of the bottom B rest on the bottom A' . When this has been done, the hooks U' , V' are disconnected from the chains B^2 , 115 B^3 , and then the hooks B^4 , B^5 are re-connected with the chains and their ropes B^6 , B^7 extending to the outside of the vat, after which the fresh material to be dyed is placed on the bottom B and then the frame O with the cover C is swung downward, to engage the cover C with the top of the material and to seat the cover on the offset A^4 , 120 as previously explained. The inactive ropes or cables U and V are 130

swung to one side, as indicated in Fig. 1, during the dyeing operation.

The worms U^3 and V^5 are adapted to be locked against accidental rotation at the time the perforated bottom B is held in the raised position shown in Fig. 4, and for this purpose brake mechanisms are provided similar to the brake mechanism above described relative to the worm P^4 , so that further description of the same is not deemed necessary, it being understood, however, that each brake mechanism consists of a brake wheel T, band T', T², lever T³, link T⁴, lever T⁵ and link T⁶, connected with the corresponding levers W² and W³; as shown in Figs. 1 and 2.

The frame O and cover C when in a raised position are preferably locked by the use of a manually-controlled catch X, fulcrumed on the overhead frame-work A⁶, to prevent the frame O and the cover C from accidentally swinging downward during the time the workmen are engaged in loading the vat A with new material to be dyed. The catch X is controlled by a downwardly extending cord X' within convenient reach of the operator.

As shown in Figs. 6 and 7, the double valve I is provided with a valve body I² and with two slide or gate valves I³, I⁴, held on a common valve stem I⁵, connected at its outer end with an operating lever I⁶, under the control of the operator. Now when the slide valves I³, I⁴ are in the position shown in Figs. 6 and 7, the pipe D' is closed to the nozzles D and communication is established between the circulating pump E and the tank pipe I', by way of the valve body I², so that the pump E can pump the dye liquor to the storage tank. When the slide valves I³, I⁴ are raised, the slide valve I⁴ closes the entrance to the tank pipe I', while the slide I³ moves into open position and establishes connection between the circulating pump E and the outflow pipe D', so that the pump E pumps the dye liquor into the vat A by way of the outflow pipe D' and nozzles D.

The double valve H, shown in detail in Fig. 8, is similar to the double valve I and is provided with a valve casing H', in which are mounted the slide or gate valves H², H³, held on a stem H⁴, connected with an operating lever H⁵. When the slide valves H², H³ are in the position shown in Fig. 8, the valve H² opens the pipe G², and the valve H³ closes the return pipe D² to the overflow chamber F, and communication is established between the pipe G² and the end of the pipe D² leading to the circulating pump E, so that when the latter is running the dye liquor in the vat A is pumped out by way of the well G, the pipe G², valve H, circulating pump E, valve I and pipe I' to the storage tank or other place.

The operation is as follows: When dyeing loose material, say a bale of cotton, it is placed in the empty vat A at the time the false perforated bottom B rests on the bottom A⁷ of the vat A, and the cover C and its supporting frame O are in an uppermost or raised position. After the material is in place on the false perforated bottom B, the frame O is swung downward into a horizontal position, and then the operator turns the screw rod N⁵, to move the cover C down into firm contact with the top of the material, to confine the same in the vat between the false perforated bottom B and the said cover C, the latter being also seated on the offset A⁴, as previously explained. Water is now run into the vat A from any suitable source until the water flows through the cover F' into the overflow chamber F, and fills the same so that the level of the water is about flush with the lower end of the cover F'. Steam is now admitted through the pipe L, to heat the water approximately to the boiling point. The clutch shifting lever S' is now moved to the left to engage the clutch member S² with the clutch member E', and then the reversible motor R' is started, to rotate the shaft E² and to actuate the circulating pump E, for the latter to draw the water out of the overflow chamber F and force the water by way of the pipe D' and nozzles D into the circulating space or chamber A² for the water to move in a circular path around the well G, and force the dirt, or other extraneous matter, from the material into the well G. The water also rises through the perforations in the false bottom B and through the material and the perforations in the cover C, to finally flow by way of the perforated cover F' into the overflow chamber F, to be returned to the circulating space A² by the circulating pump E. The dissolved dye stuff is added to the water in the tank to form a dye liquor, which is now circulated through the vat A and the material, the same as the water and as above described. This operation is continued until the dye liquor has dyed the material and is sufficiently exhausted to warrant its removal, which is done as follows: The valves H and I are shifted to the positions shown in Figs. 7 and 8, so that the circulating pump draws the dye liquor out of the vat A by way of the well G, pipe G², valve H, pipe D², circulating pump E, valve I and pipe I', to a storage tank or other place of discharge, that is, if the dye liquor is still valuable it is stored for further use, but if its dyeing properties have been spent it may be allowed to run to waste from the pipe I'.

If it is desired to follow the dyeing operation with clear water for washing the material the valve D³ is closed, the valve J' is opened and the valve I is shifted to move

the slide valve I^3 into open position, and the valve K' is opened, so that the pump E now draws clear water in through the pipe J , valve J' , pipe D^2 , and forces the water out by way of the pipe D' and the nozzles D into the circulating space A^2 , from which the water rises through the perforations of the false bottom B through the material, the perforations of the cover C , to flow into the overflow chamber F and drain out of the same by way of the pipe K , to a suitable place of discharge. After the washing operation is completed, the water in the vat is drawn out of the same. The circulating pump E is now stopped by the operator shifting the lever S' to the intermediate position shown in Fig. 1. The operator now turns the screw rod N^5 , so as to unseat the cover C , and then the frame O is unlocked by removing the pin O^3 and swinging the link O^2 into open position, as shown in Fig. 4. The operator now shifts the lever S' to the right, so as to connect the clutch member S with the clutch member Q^4 , and then the motor R' is started, to rotate the shaft Q . The operator now swings the lever P^7 to the right, to engage the clutch member P^6 with the clutch member P^5 , to cause turning of the drum P' , as previously described, with a view to wind up the rope or cable P and thereby swing the frame O and with it the cover C upward into an open position. The latch X is now engaged with the frame O , to lock the same in place against accidental downward swinging movement. The lever P^7 is now swung in the reverse direction of the arrow a' , so that the brake for the worm P^4 is applied, as before stated, to hold the drum P' against accidental return movement. The operator now pulls the chains B^2 , B^3 upward, by the use of the ropes B^6 , B^7 , and then connects the chains B^2 , B^3 with the hooks U' , V' , after which the levers W^6 , V^6 are moved to the right, to throw the clutch members W and W' into engagement with the clutch members U^6 , V^6 , to rotate the drums U^2 and V^2 in unison, to wind up the ropes or cables U and V , with a view to lift the false perforated bottom B to the top of the vat A with the material resting on the said bottom. The rotation of the drum V^2 is now stopped by the operator shifting the lever V^6 back to normal position, to throw the clutch member W' out of engagement with the clutch member V^6 . The rotation of the drum U^2 is continued, so that the perforated false bottom B is now swung into the inclined discharging position, shown in Fig. 4, for the dyed material to slide off the said bottom to one side of the machine, into a suitable supporting receptacle or other device.

It is understood that after the perforated false bottom B reaches the discharging po-

sition, the lever W^6 is moved to the left, to move the clutch member W out of engagement with the clutch member U^6 and to apply the brake for the worm U^5 . When it is desired to return the perforated false bottom B into the vat A , then the motor R' is reversed, to rotate the shaft Q in the opposite direction, and then the lever W^6 is moved to the right to engage the clutch member W with the clutch member U^6 , to rotate the drum U^2 in the opposite direction, for the rope or cable U to unwind and to allow the false perforated bottom to swing into horizontal position, and when this takes place the other drum W^2 is started to unwind the rope or cable W , to allow the false perforated bottom B to descend in the vat A , until its lugs B' rest on the bottom A' , and the above described operation is repeated.

When dyeing yarns on a beam M , the solid cover C^4 is secured to the underside of the perforate cover C by the screws C^5 , and the plug M^5 is unlocked and removed, and then the beam M with the yarn thereon is placed on the false bottom B , raised to the top of the vat A for the purpose, and while the covers C , C^4 are held in raised position. The bottom B with the beam M thereon is now lowered into the vat A and when the false bottom B rests on the vat bottom A' , then the beam M is shifted to the right to engage the open end of the hub M' with the seat F^4 , and then the wedge M^4 is inserted to draw the hub M' in firm contact with the packing F^3 . The covers C , C^4 are now swung down and locked in place. The circulating pump E is now started to circulate the dye liquor through the yarn on the beam M , as previously explained, the dye liquor passing from the vat A by way of the perforate hub M' into the overflow chamber F , to be returned to the circulating pump. A washing of the yarn on the beam M may follow by proceeding in the manner above described relative to washing the dyed loose material. After the dyeing operation of the yarn is completed, the covers C , C^4 are swung up into open position, the wedge M^4 is withdrawn and the beam M is shifted to the left until the shaft M^3 clears the seat F^4 , and then the false bottom B with the beam M thereon is raised to the top of the vat, to permit of conveniently removing the beam M from the false bottom B . Another beam with yarn thereon can now be placed in position on the false bottom B , and the above described operation is then repeated.

Having thus described my invention, I claim as new and desire to secure by Letters Patent:

1. A dyeing machine provided with a vat, a movable false bottom and a cover for said

vat, mechanism for manipulating the vat cover and the false bottom, a flexible connection between the false bottom and the bottom of the vat, and means for circulating a liquid through the vat.

2. A dyeing machine provided with a vat, a movable perforated false bottom in the vat, a cover for said vat, mechanism for manipulating the vat cover and the false bottom, a flexible connection between one end of the false bottom and the opposite end of the vat, and a circulating system for circulating a liquid through the vat.

3. A dyeing machine provided with a vat, a chamber at one end of the vat and communicating therewith, a movable false bottom and a hinged cover for said vat, an overhead mechanism for swinging the cover up and down and for raising and lowering the false bottom and tilting it when raised, means for holding the false bottom in the tilted position, a circulating system for circulating liquid through the said vat and chamber, the said circulating system having a pump, and a reversible motor for actuating the pump, and also for actuating the said overhead mechanism in either direction.

4. A dyeing machine provided with a vat, a chamber adjacent the said vat and having an inclined top provided with openings for the liquid to overflow from the vat into the said chamber, a cover for the vat, a perforated false bottom for the vat, mechanism for manipulating the vat cover and the false bottom, a circulating means connected with the said vat and chamber, and means for heating the liquid in said chamber.

5. A dyeing machine provided with a vat, a false bottom therein, means for raising the false bottom out of the vat into an inclined discharging position, and flexible retaining means connecting one end of the false bottom with the opposite end of the vat bottom for holding the said false bottom against movement during the time the dyed material slides off the said false bottom.

6. A dyeing machine provided with a vat, a false bottom therein, means for raising the said false bottom out of the vat into an inclined discharging position, and chains connecting the uppermost end of the said inclined bottom with the vat bottom at the opposite end.

7. A dyeing machine provided with a vat, an overflow chamber having an overflow connection therewith, a perforate hinged cover for said vat, a perforate false bottom for the vat, mechanism for swinging the cover up and down, mechanism for raising and lowering the false bottom, and tilting it when raised, means for holding the false bottom in the tilted position, and a circulating pump for the liquid connected with the said vat and chamber.

8. A dyeing machine provided with a vat,

a chamber at one end of the vat and communicating therewith, a perforate false bottom in said vat, a cover for said vat, means for raising and lowering the cover, means for lowering the false bottom into the vat and raising it out of the vat into an inclined discharging position, flexible retaining means connecting one end of the false bottom with the opposite end of the vat bottom, and a circulating pump for the liquid connected with the said vat and chamber.

9. In a dyeing machine, the combination of a reversible motor, a vat having a movable false bottom and a cover, a pump for circulating a liquid through the vat, a mechanism for raising or lowering the said false bottom and tilting it, when raised, into a discharge position, a mechanism for swinging the said cover up or down, the said mechanisms having a common driving shaft, manually controlled couplings for connecting the said common driving shaft with the said mechanisms, and means for connecting the said motor with the said pump or with the said driving shaft.

10. In a dyeing machine, the combination of a reversible motor, a vat having a movable false bottom and a hinged cover, an overhead mechanism for raising or lowering the said false bottom and tilting it, when raised, into a discharge position, an overhead mechanism for swinging the said cover up or down, the said overhead mechanisms having a common driving shaft, manually-controlled couplings for connecting the said common driving shaft with the said overhead mechanisms, a circulating pump connected with the said vat for circulating a liquid through the vat, and a manually-controlled double clutch for connecting the said motor with the said pump or the said driving shaft for the overhead mechanisms.

11. In a dyeing machine, the combination of a reversible motor, a vat having a movable false bottom and a hinged cover, an overhead mechanism for raising or lowering the said false bottom and tilting it, when raised, into a discharge position, an overhead mechanism for swinging the said cover up or down, the said overhead mechanisms having a common driving shaft, manually-controlled coupling mechanisms for connecting the said common driving shaft with the said overhead mechanisms, brakes controlled by the said coupling mechanisms, a circulating pump connected with the said vat for circulating a liquid through the vat, and a manually-controlled double clutch for connecting the said motor with the said pump or the said driving shaft for the overhead mechanisms.

12. A dyeing machine, provided with a vat having a circulating space, an overflow chamber, and a well approximately central in the said circulating space, nozzles in the

said circulating space, a circulating pump, pipes connected with the said nozzles, the said overflow chamber, the said well and the said circulating pump, and valves in the said pipes for controlling the flow of different liquids through the vat.

13. A dyeing machine, provided with a vat having a circulating space, an overflow chamber, and a well approximately central in the said circulating space, nozzles in the said circulating space, a circulating pump, pipes connected with the said nozzles, the said overflow chamber, the said well and the said circulating pump, and valves in the said pipes for controlling the flow of the different liquids through the vat, sundry of the said valves being double and forming by-passes.

14. A dyeing machine, provided with a vat, a false perforated bottom in the said vat for supporting the material to be dyed and forming with the bottom of the vat a circulating space, a perforate cover resting on the material in the vat, an overflow chamber at one end of the vat and having its entrance above the said cover, a circulating pump, an outflow pipe connecting the discharge end of the said pump with the said circulating space, a return pipe connecting the said overflow chamber with the inlet end of the said pump, a valve in the said return pipe, a valved outlet pipe leading from the said overflow chamber, and a valved water supply pipe connected with the said return pipe between the valve thereof and the circulating pump.

15. A dyeing machine, provided with a vat, a false perforated bottom in the said vat for supporting the material to be dyed and forming with the bottom of the vat a circulating space, a perforate cover resting on the material in the vat, an overflow chamber at one end of the vat and having its entrance above the said cover, a circulating pump, a well in the said circulating space, an outflow pipe connecting the discharge end of the said circulating pump with the said circulating space, a return pipe connecting the said overflow chamber with the inlet end of the said pump, an outlet pipe leading from the said well, and a valved connection between the said well outlet pipe and the said return pipe for closing the latter to the overflow chamber and connecting the well outlet pipe with the inlet end of the said pump.

16. A dyeing machine, provided with a vat, a false perforated bottom in the said vat for supporting the material to be dyed and forming with the bottom of the vat a circulating space, a perforate cover resting on the material in the vat, an overflow chamber at one end of the vat and having its entrance above the said cover, a circulating pump, a well in the said circulating

space, an outflow pipe connecting the discharge end of the said circulating pump with the said circulating space, a return pipe connecting the said overflow chamber with the inlet end of the said pump, an outlet pipe leading from the said well, a valved connection between the said well outlet pipe and the said return pipe for closing the latter to the overflow chamber and connecting the well outlet pipe with the inlet end of the said pump, a valve in the said return pipe and located between the pump and the said valved connection, a valved water supply connected with the said return pipe at a point between the said valve and the pump, and a valved discharge pipe leading from the said overflow chamber.

17. A dyeing machine, provided with a vat, a false perforated bottom in the said vat for supporting the material to be dyed and forming with the bottom of the vat a circulating space, a perforate cover resting on the material in the vat, an overflow chamber at one end of the vat and having its entrance above the said cover, a circulating pump, a well in the said circulating space, an outflow pipe connecting the discharge end of the said circulating pump with the said circulating space, a return pipe connecting the said overflow chamber with the inlet end of the said pump, an outlet pipe leading from the said well, a valved connection between the said well outlet pipe and the said return pipe for closing the latter to the overflow chamber and connecting the well outlet pipe with the inlet end of the said pump, a storage tank pipe leading to a storage tank, and a valved connection between the said outflow pipe and the said storage tank pipe to close the outflow pipe to the circulating space and to connect the outflow pipe with the said storage tank pipe.

18. A dyeing machine provided with a vat, a false perforated bottom in the vat for supporting the material to be dyed, a perforated cover in the said vat, a swing frame on the said vat, supporting means on the swing frame and carrying the said cover, means for adjusting the supporting means to press the cover to its seat or to unseat the same, an overhead drum, a rope winding and unwinding on the said drum and connected with the said swing frame to swing the latter up or down, a pair of overhead drums, ropes winding and unwinding on the said pair of overhead drums and connected with the said false bottom, a common driving shaft for the said drums, a reversible motor connected with the said shaft for driving the same in opposite directions, and manually controlled independent couplings for connecting the said shaft with either of the said drums.

19. A dyeing machine provided with a

vat, a false perforated bottom in the vat for supporting the material to be dyed, a perforated cover in the said vat, a swing frame on the said vat, adjustable supporting means 5 on the said swing frame and carrying the said cover, an overhead drum, a rope winding and unwinding on the said drum and connected with the said swing frame to swing the latter up or down, a pair of overhead drums, ropes winding and unwinding on the said pair of overhead drums and connected with the said perforated false bottom, a common driving shaft for said drums, manually controlled independent 10 couplings for connecting the said shaft with either of the said drums, a circulating pump connected with the said vat for circulating a liquid through the vat, a reversible motor, and means for connecting the said motor 15 with the said pump or the said driving shaft.

20. A dyeing machine provided with a vat, a false perforated bottom in the vat, a cover for the vat, a swing frame mounted 25 on the vat, adjustable supporting means including bell crank levers fulcrumed on the swing frame and connected with the cover, means for adjusting said supporting means to press the cover to its seat or to unseat 30 the same, a mechanism for swinging the hinged frame and cover up or down, a mechanism for raising and lowering the said false bottom, the said mechanisms having a common driving shaft, and a reversible 35 motor connected with the said shafts for driving the same in opposite directions.

21. A dyeing machine provided with a vat, a false perforated bottom in the vat for supporting the material to be dyed, a cover 40 in the said vat, a swing frame fulcrumed on the said vat, bell crank levers fulcrumed on the swing frame and connected by links with the said cover, means for adjusting the bell crank levers to press the cover to its 45 seat or to unseat the same, mechanism for swinging the hinged frame and cover up or down, mechanism for raising or lowering the false bottom and tilting the same when raised, a common driving shaft for said 50 mechanisms, a reversible motor connected with the said shaft, for driving the same in opposite directions, manually controlled driving connections for connecting the said shaft with either of said mechanisms, and a 55 brake mechanism for each of the said driving connections.

22. A dyeing machine provided with a vat, a false perforated bottom in the said vat for supporting the material to be dyed, 60 a perforated cover adapted to be seated in the vat on top of the material, a swing frame fulcrumed on the vat, levers fulcrumed on the swing frame and connected with the cover, means for adjusting said 65 levers to press the cover to its seat or to

unseat the same, a circulating pump, connections between the said pump and vat to circulate a liquid through the vat and the material contained therein, overhead reversible mechanisms connected with the said 70 false bottom and the said cover, a common driving shaft for the said reversible mechanisms, a reversible engine, and mechanism for connecting the said engine with either the said pump or the said driving shaft. 75

23. A dyeing machine provided with a vat, a false perforated bottom therein for supporting the material to be dyed, a perforate cover adapted to be seated in the said vat, a swing frame fulcrumed on the said vat, bell crank levers fulcrumed on the said swing frame, links on the said bell crank levers and supporting the said cover, a link connecting the bell crank levers with each other and carrying a pivoted nut, and a screw rod supported on the swing frame screwing in the said nut. 80

24. A dyeing machine provided with a vat, a false perforated bottom therein for supporting the material to be dyed, a perforate cover adapted to be seated in the said vat, a swing frame fulcrumed on the said vat, bell crank levers fulcrumed on the said swing frame, links on the said bell crank levers and supporting the said cover, a link 90 connecting the bell crank levers with each other and carrying a pivoted nut, a screw rod screwing in the said nut, and a collar journaled on the said swing frame and in which the said screw rod is mounted to turn. 100

25. In a dyeing machine, the combination of a reversible motor, a vat, a false perforated bottom in the said vat and forming with the bottom of the vat a circulating space, a cover for the vat, an overflow chamber at one end of the vat, means for heating the liquid in said chamber, an overhead mechanism for raising or lowering the false bottom and tilting it when raised into a discharge position, means for holding the said 105 false bottom in the discharge position, an overhead mechanism for swinging the said cover up or down, the said overhead mechanisms having a common driving shaft, manually controlled couplings for connecting the said common driving shaft with the said overhead mechanisms, a circulating pump connected with the said vat and chamber for circulating a liquid through the same, and a manually controlled double clutch for connecting the said motor with the said pump or with the said driving shaft for the overhead mechanisms. 110

26. A dyeing machine provided with a vat having a circulating space, an overflow 125 chamber, means for heating the liquid in said overflow chamber, a well in the said circulating space, nozzles in the said circulating space, an outlet pipe leading from the well, a circulating pump, pipes connected 130

with the said nozzles, the said overflow chamber, the said well and the said circulating pump, and valves in the said pipes for controlling the flow of different liquids 5 through the vat.

27. A dyeing machine provided with a vat having a circulating space, an overflow chamber at one side of the vat, a well in the center of the circulating space, nozzles in 10 the said circulating space, a circulating pump, pipes connected with the said nozzles, the said overflow chamber, the said well and the said circulating pump, valves in the said pipes for controlling the flow of liquids 15 through the vat, and a valve controlled outlet pipe leading from said overflow chamber.

28. A dyeing machine provided with a vat, a false perforated bottom in the vat, a cover for the vat, a swing frame mounted 20 on the vat, adjustable supporting means including bell crank levers fulcrumed on the swing frame and connected with the cover, means for adjusting said supporting means to press the cover to its seat or to unseat the 25 same, mechanism for swinging the hinged frame and cover up or down, and mecha-

nism for raising or lowering the false bottom and tilting the same when raised.

29. A dyeing machine provided with a vat having a movable false bottom and a hinged 30 cover, a mechanism for raising or lowering the false bottom and tilting it when raised, a swing frame fulcrumed on the vat, bell crank levers fulcrumed on the swing frame and connected with the cover, means for 35 swinging the bell crank levers to move the cover to or from its seat, a mechanism for swinging the swing-frame and cover up or down, a chamber adjacent to the vat, and communicating therewith, a circulating 40 pump connected with the said chamber and vat for circulating a liquid through the same, a motor, and means for connecting the said motor with the said pump or the said mechanisms.

In testimony whereof I have signed my name to this specification in the presence of two subscribing witnesses.

JULIUS LEISEL.
